US0D1059954S

(12) United States Design Patent (10) Patent No.: US D1,059,954 S
(45) Date of Patent: * Feb. 4, 2025

(54) CUP

(71) Applicant: YETI Coolers, LLC, Austin, TX (US)

(72) Inventors: Desiree Hunter, Austin, TX (US); Liza Morris, Austin, TX (US); Roy Joseph Seiders, Austin, TX (US); Mark Carlson Rane, Austin, TX (US)

(73) Assignee: YETI Coolers, LLC, Austin, TX (US)

() Term: 15 Years

(21) Appl. No.: 29/813,383

(22) Filed: Oct. 28, 2021

Related U.S. Application Data

(63) Continuation of application No. 29/669,435, filed on Nov. 8, 2018, now Pat. No. Des. 934,633.

(51) LOC (15) Cl. 07-01

(52) U.S. Cl.

USPC D7/509

(58) Field of Classification Search

(57) CLAIM

The ornamental design for a cup, as shown and described.

DESCRIPTION

FIG. 1 is a top, front, left perspective view of a cup showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting the remainder of the cup show features that form no part of the claimed design.

1 Claim, 4 Drawing Sheets
